UNITED STATES PATENT OFFICE.

IRVING A. HUNTING, OF PLAINFIELD, NEW JERSEY, ASSIGNOR TO WILLIS S. MORSE,
OF PHILADELPHIA, PENNSYLVANIA.

WEB-TENSION-CONTROLLING MECHANISM.

1,103,143.

Specification of Letters Patent. Patented July 14, 1914.

Application filed September 1, 1910. Serial No. 580,104.

To all whom it may concern:

Be it known that I, IRVING A. HUNTING, a citizen of the United States, residing at Plainfield, in the county of Union and State of New Jersey, have invented certain new and useful Improvements in Web-Tension-Controlling Mechanism, of which the following is a specification, reference being had to the accompanying drawings.

10 This invention relates to improvements in mechanisms for controlling the tension of a web or continuous sheet or strip of material, such as paper or textile fabric; and an object of this invention is to provide a mechanism of the character just described which will be electrically-operated, which will be comparatively simple in construction, which may be readily applied to machines (such as printing presses) now in common use, which 20 will be quick in action and efficient in operation and the initial cost of which will be relatively low.

In the drawings illustrating the principle of this invention and the best mode now known to me of applying that principle, Figure 1 is a side elevation of so much of a web-tension controlling mechanism as is necessary to illustrate this invention; Fig. 2 is a detail which illustrates in side elevation the brake-wheel, the brake-shoes and the parts carried by the latter for controlling the pressure on the brake-wheel; Fig. 3 is a view looking in the direction of the arrow A in Fig. 2; Fig. 4 is a detail showing the devices 35 for swinging the switch-arm and is a section on the line B—B of Fig. 1; and Fig. 5 is a diagrammatic view of the electrical connections.

The upright or standard *a* supports one 40 end of the roll-holding shaft *b* the other end of which is supported in an entirely similar manner by an opposite standard (not shown). Upon one end of the shaft *b* is mounted a friction-pulley or brake-wheel *c* formed with a peripheral or circumferential groove *d* in its rim-face. Mounted in the standard *a* is a screw-stud *e* the threads *f* of which are engaged by the threads formed on the interior wall of a bushing or sleeve *g*. 45 On one end of the latter is formed a flange or integral collar *h* and on its other end it carries a hand-wheel *i*. Between the inner end of the latter and the flange *h* are pivotally mounted the lower ends of the brake-

shoes *j*, *k*. By turning the hand-wheel *i* 55 the latter may be adjusted laterally along the screw-stud *e*. In the upper end of the brake-shoe *k*, is formed a journal-bearing *k'* for the flexible shaft *m* on the threaded end *m'* of which is mounted the nut *n* and on the 60 other end of which is mounted a worm-wheel *o*. The inner faces of the brake-shoes *j*, *k* enter the groove *d* in the face of the brake-wheel *c* and bear against the walls of the groove. On the brake-shoe *k* is mounted 65 an electric motor *p* on one end of the armature-shaft *q* of which is mounted a worm *r* which meshes with a worm-wheel *s* on the lower end of the upright shaft *t* which is mounted rotatably in the journal-box *u* 70 carried by the brake-shoe *k*. On the upper end of the shaft *t* is mounted a worm *v* which meshes with the worm-wheel *o* carried by the flexible shaft *m*. Obviously rotation 75 of the armature-shaft *q* will cause rotation of the latter shaft and the brake-shoes *j*, *k* will be brought closer together or will fall apart at their upper ends, depending upon the direction of rotation of the armature-shaft *q*, the friction between the upper end 80 of the brake-shoe *j* and the inner face or end of the nut *n* serving to keep the latter from turning. Hence, the nut *n* will travel along the threaded end *m'* of the shaft *m* as the latter is rotated by the armature- 85 shaft *q*.

On the roll-holding shaft *b* is mounted a roll *w* of material (as paper to be printed) and from this roll *w* extends or is led a web *x*. The latter breaks over the idler-rolls *y*, *z* in its passage to the printing devices (not shown). The upper idler-roll *y* is mounted free to turn on a rock-shaft *2* one end of which is supported rotatably in a post *3* which rises from the horizontal frame-member or beam *4*. To the rock-shaft *2* is fastened a rocker-arm *5* the free end of which carries one end of the shaft *6* on which turns the other idler-roll *z*. It is thought unnecessary to illustrate the mounting of the opposite end of the shaft *6*, since it is the same as that of the end herein shown and just described; and the same is true of the other end of the rock-shaft *2*. As is shown in Fig. 4, an end of the latter projects beyond 100 the post *3* and on this projecting end is fastened a switch-arm *7* to the upper end of which is pivotally fastened one end of a rod

8 the other end of which extends into an exteriorly-threaded bushing 9 mounted in the interiorly-threaded bracket 10 fastened to the upright or standard *a*. Near its pivoted end the rod 8 is formed with a shoulder 11 against which presses one end of a coil-spring 12 mounted on the rod 8. The other end of this coil spring bears against the inner end of the threaded bushing 9 by which the tension of the spring may be adjusted. This tension tends to throw the upper end of the switch-arm 7 to the right in Figs. 1 and 5. On the beam 4 is mounted a slab of marble or slate 13 (any suitable insulating material may be used) on which is arranged a series of contact-blocks 14 over which are arranged to rub a pair of brushes 15 carried by the lower end of the switch-arm 7 and suitably insulated from each other. Current from the mains 16 is led to the field coils 17 of the motor *p* (Fig. 5) and, through the brushes 15 and the contact-blocks 14 and the connections shown, to the armature *p'*. The terminals of an electric glow-lamp 18 are connected to the end-blocks 19 of the series 14 and to the blocks 20 adjacent to the central block 21. To the latter is connected a terminal of the electric glow-lamp 18' the other terminal of which is connected to the contact-block 22 which lies between one of the end-blocks 19 and one of the blocks 20. One of the armature brushes 23 is connected to the central block 21, while the other armature brush is connected to the block 22' which lies between the other end-block 19 and the other block 20. The blocks 22, 22' are electrically connected with each other. This arrangement of the glow-lamps 18, 18' serves to prevent sparking, as the switch-arm is thrown to shift the brushes 15 from one block to another of the series 14, the lamp 18' serving to relieve the inductive discharge of the armature coil and the lamp 18 serving to relieve the inductive discharge of the line. When the tension of the web is normal, the switch-arm 7 is in the neutral position shown in Figs. 1 and 5. When the tension of the web increases or rises above the normal tension, the lower end of the switch-arm 7 is thrown to the right in Figs. 1 and 5 and current will flow through the armature *p'*. When the tension of the web falls below the normal, the coil-spring 12 throws the lower end of the switch-arm 7 to the left in these figures and current flows in the opposite direction through the armature *p'*. Thus, the tension of the web is made through an electrically-operated device to regulate itself, the direction of rotation of the armature shaft *q* controlling the pressure of the brake-shoes *j*, *k* against the brake-wheel *c* and thereby the tension of the web *x*. Should the latter break, the switch-arm will be thrown to its extreme position

on the left of Figs. 1 and 5 and the left-hand brush 15 will rest on the left-hand block 19; while should the working of the apparatus become so abnormal as to throw the switch-arm to its extreme position on the right of the figures just named, the right-hand brush 15 will rest on the right-hand block 19. When the switch-arm is thrown into either of these extreme positions, the circuit is broken and, therefore, the current is varied. Moreover, when the switch-arm is thrown to one side of a vertical line through the center of the central block 21, and then to the other side of that vertical line, the direction of the current is changed. 75 80

I claim:

1. A web-tension controller having a rotary roll-supporting shaft from which the web is pulled; devices for retarding the rotation of said shaft and thereby increasing 85 the tension of the web; electrically operated mechanism arranged to operate said devices; and means for varying the current which drives said mechanism, said means being mounted free to move in response to variations in the tension of the web.

2. A web-tension controller having a rotary roll-supporting shaft from which the web is pulled; devices for retarding the rotation of said shaft and thereby increasing 95 the tension of the web; electrically operated mechanism arranged to operate said devices; and means for reversing the direction of the current which drives said mechanism and thereby the direction of movement of the latter, said means being mounted free to move in response to variations in the tension of the web and being automatically operated by the tension of the web to control the supply of current to said mechanism. 100 105

3. A web-tension controller having a rotary roll-supporting shaft from which the web is pulled; devices for retarding the rotation of said shaft and thereby increasing 110 the tension of the web; electrically operated mechanism arranged to operate said devices; a shaft arranged to rock in response to variations in the tension of the web and automatically operated by the tension of the web; and an electrical make-and-break device connected with said mechanism and controlled by the rocking of said shaft to control the supply of current to said mechanism. 115

4. A web-tension controller having a rotary roll-supporting shaft from which the web is pulled; devices for retarding the rotation of said shaft and thereby increasing 120 the tension of the web; electrically operated mechanism arranged to operate said devices; an electrical make-and-break device electrically connected with said mechanism for controlling the supply of current thereto; and means automatically operated by the 125 130

tension of the web and mounted free to move in response to variations therein for actuating said make-and-break device.

5. A web-tension controller having a rotary roll-supporting shaft from which the web is pulled; devices for retarding the rotation of said shaft and thereby increasing the tension of the web; electrically operated mechanism arranged to operate said devices and carried by one of the latter; and means for varying the current which drives said mechanism, said means being automatically operated by the tension of the web and being mounted free to move in response to variations therein.

6. A web-tension controller having a rotary roll-supporting shaft from which the web is pulled; devices for retarding the rotation of said shaft and thereby increasing the tension of the web; electrically operated mechanism arranged to operate said devices; means for varying the current which drives said mechanism, said means being automatically operated by the tension of the web and being mounted free to move in response to variations therein; and devices arranged to prevent sparking at said means, when the current is varied.

7. A web-tension controller having a rotary roll-supporting shaft from which the web is pulled; devices for retarding the rotation of said shaft and thereby increasing the tension of the web; electrically operated mechanism arranged to operate said devices; means for varying the current which drives said mechanism; and a web-support which is connected with said means and which moves in response to variations in the tension of the web and is automatically operated by the same to actuate said means and control said devices to preserve a constant tension on the web.

8. A web-tension controller having a rotary roll-supporting shaft from which the web is pulled and which is rotated by the tension of the web; devices for retarding the rotation of said shaft and thereby increasing the tension of the web; mechanism for throwing said devices into and out of operation to vary the retarding action thereof; an electric motor for driving said mechanism; a switch for varying the intensity and direction of the current supplied to said motor; and a web-support over which the web breaks and which is connected with said switch and moves in response to variations in the tension of the web and is automatically operated by the same to actuate said switch and control said devices to preserve a constant tension on the web.

9. The combination, in a tension regulator for printing presses and the like having a web-supply-roll shaft and a guide or compensating roll, of a movable member mounted to be acted on by the web after the same

passes the guide or compensating roll and free to respond to variations in the tension of said web, an electric current controller actuated by said movable member, means for retarding or permitting acceleration of the web-supply-roll shaft, and mechanism including an electric motor operable independently of the web-supply-roll shaft and controlled by variations in the tension of the web above or below normal for varying the action of said retarding means in accordance with variations in the position of said movable member.

10. The combination, in a tension regulator for printing presses and the like having a web-supply-roll shaft and a guide or compensating roll, of a movable member bearing on the web beyond the compensating roll and free to respond to variations in the tension of the web, mechanism including an electric motor operable independently of the web-supply-roll shaft, and brake mechanism connected thereto for retarding or permitting acceleration of the rotation of the web-supply-roll shaft, a controller in circuit with said electric motor for controlling the action of the same, and means for operating said controller by the movable member, said means occupying its neutral or normal position on the controller when the web is under proper working tension and movable out of said position to actuate the motor in response to changes in the tension of said web.

11. The combination, in a tension regulator for printing presses and the like having a web-supply-roll shaft and a guide or compensating roll, of a braking structure connected to the web-supply-roll shaft, a brake shoe operative thereon, an electric motor operable independently of the web-supply-roll shaft, means for operatively connecting said electric motor with the brake shoe to vary the pressure exerted by said shoe upon the braking structure, a controller in circuit with said motor, and a movably-mounted member bearing upon the web beyond the compensating or guide roll and having a part movable over said controller and arranged to be actuated by the tension of the web passing through the press for operating said controller, said last-named part occupying a neutral or normal position while the web is under proper working tension, and movable out of said position to actuate the motor in response to variations in the tension of the web.

12. The combination, in a tension regulator for printing presses and the like having a compensating or guide roll, of a shaft for supporting a roll of paper, a braking structure thereon, a brake shoe operative on said structure, a lever operatively connected with said shoe, a movable nut connected with said lever, a screw shaft for changing the position of said nut to operate the lever, and

an electric motor for operating said screw shaft, a controller in circuit with said motor, and a pivotally-mounted structure having one part supported by the web in the 5 press beyond the compensating or guide roll and having another part operable over the said controller, the last-named part of the structure occupying a neutral or normal position on said controller while the 10 web is under proper working tension and movable out of said position to cause the motor in circuit to respond to a variation in the tension of the web.

13. The combination, in a printing press 15 and the like having a web-supply-roll shaft, of a plurality of rolls beyond the same over which the web passes from the supply-roll, one of said rolls being a compensating roll, a tension regulator comprising two arms 20 turnable in unison about a common axis, one of said arms resting on the web beyond said compensating roll and being sensitive to and responsive to variations in the tension of the web, an electric controller located in operative 25 relation to the other of said arms, said last-named arm occupying a neutral or normal position on the controller so long as the web is under proper working tension and automatically responding to the movement 30 of the companion arm by either an increase or decrease in the tension of the web, and an electric motor in circuit with said controller inoperative or inactive while the second-named arm is in the said position but instantly 35 rendered operative or active when said arm is moved in either direction therefrom, a brake mechanism for the web-supply-roll shaft and operating means therefor controlled by said motor.

40 14. In a tension regulator for printing presses having a web-supply-roll shaft and a plurality of rolls uniting the same over which the web passes, one of said second-named rolls being a compensating roll, said 45 regulator including a rockable lever mechanism having one portion supported on the web beyond the compensating roll and being sensitive and responsive to variations in the tension thereon, a current controller, said 50 lever mechanism having a part maintained in neutral or normal position relative to the current controller while the web is under proper working tension and movable therefrom in one direction or the other in response 55 to variations in the tension of the web passing against the other portion of the lever mechanism, an electric motor operable independently of the web-roll shaft in circuit with the current controller and inactive or 60 inoperative so long as the lever mechanism is in said position, but energized and rendered operative or active when the lever mechanism is actuated relatively to the current controller by a change in the tension of 65 the web, a braking mechanism for the sup-

ply-roll shaft and means connecting the motor with the braking mechanism operating to increase or reduce pressure on the web-supply-roll shaft in response to changes in the tension of the web.

15. The combination, in a tension regulator for printing presses and the like having a compensating or guide roll, of a movable member having its free end supported on the web beyond the compensating roll 70 and made sensitive and responsive to variations in the tension of said web, a current controller, a member connected to and responding in unison with fluctuations of said member, the latter occupying a neutral or 75 normal position on the current controller so long as the web is under proper working tension and movable either side of said position in response to web-tension changes, means for retarding or permitting increase 80 in the speed of rotation of the roll from which the web is supplied, and mechanism including a normally inactive or inoperative electric motor operable independently 85 of the web-supply-roll shaft in circuit with the current controller and made active and quickly responsive to the movement of said pivoted member in either direction from its normal or neutral position for varying the retardation caused by said means in accordance 90 with variations in the tension of the web.

16. In a tension regulator for printing presses and the like having a compensating or guide roll over which the web passes, the combination with the web-supply-roll shaft and braking mechanism therefor, of mechanism interposed between the web and braking mechanism for automatically controlling the tension of the web, said mechanism comprising an electric motor operable independently of the web shaft, a pivoted lever having one end supported on the web beyond the compensating roll, said lever being sensitive and responsive to variations 100 in the tension of the web, an arm movable by the lever, a current controller over which the arm is movable in either direction from its neutral or normal position whereby the motor is energized in quick response to variations in the tension of the web, said arm occupying the neutral or normal position on the controller and the motor being inactive or inoperative when the web is under proper working tension, and connections between 110 the motor and the braking mechanism controlled by the former and in turn retarding or permitting acceleration of the tension of the supply roll.

17. The combination, in a tension regulator for printing presses and the like having a web-supply-roll, of a movable member mounted to be acted on by the web and free to respond to variations in the tension of said web, an electric current controller actuated 120

- by said movable member, means for retarding the web-supply-roll shaft, and mechanism including an electric motor operable independently of the web-supply-roll shaft 5 and controlled by variations in the tension of the web above or below normal for varying the action of said retarding means in accordance with variations in the position of said movable member.
18. The combination, in a tension regulator for printing presses and the like having a web-supply-roll shaft, of a movable member bearing on the web and free to respond to variations in the tension of the web, mechanism including an electric motor operable independently of the web-supply-roll shaft, and brake mechanism connected thereto for retarding the rotation of the web-supply-roll shaft, a controller in circuit with said electric motor for controlling the action of the same, and means for operating said controller by the movable member, said means normally occupying its neutral position on the controller when the web is under proper working tension and movable out of said position to actuate the motor in response to changes in the tension of said web.
19. The combination, in a tension regulator for printing presses and the like having a web-supply-roll shaft, of a braking structure connected to the web-supply-roll shaft, a brake shoe operative thereon, an electric motor operable independently of the web-supply-roll shaft, means for operatively connecting said electric motor with the brake shoe to vary the pressure exerted by said shoe upon the braking structure, a controller in circuit with said motor, and a movably-mounted member bearing upon the web and having a part movable over said controller and arranged to be actuated by the tension of the web passing through the press for operating said controller, said last-named part of the controller occupying a neutral or normal position while the web is under proper working tension, and movable out of said position to actuate the motor in response to variations in the tension of the web.
20. The combination, in a tension regulator for printing presses and the like, of a shaft for supporting a roll of paper, a braking structure thereon, a brake shoe operative on said structure, a lever operatively connected with said shoe, a movable nut connected with said lever, a screw shaft for changing the position of said nut to operate the lever, and an electric motor for operating said screw shaft, a controller in circuit with said motor, and a pivotally-mounted structure having one part supported by the web in the press and having another part operable over the said controller, the last-named part of the structure occupying a neutral or normal position on said controller 60 while the web is under proper working tension and movable out of said position to cause the motor in circuit to respond to a variation in the tension of the web.
21. In a printing press and the like having a web-supply-roll shaft, a tension regulator comprising two arms turnable in unison about a common axis, one of said arms resting on the web and being sensitive and responsive to variations in the tension of the web, an electric controller located in operative relation to the other of said arms, said last-named arm occupying a neutral or normal position on the controller so long as the web is under proper working tension and automatically responding to the movement 75 of the companion arm by either an increase or decrease in the tension of the web, and an electric motor in circuit with said controller inoperative or inactive while the second-named arm is in the said position but instantly rendered operative or active when said arm is moved in either direction therefrom, a brake mechanism for the web-supply-roll shaft and operating means therefor controlled by said motor.
22. A tension regulator for printing presses having a web-supply-roll shaft, said regulator including a rockable lever mechanism having one portion supported on the web and being sensitive and responsive to variations in the tension thereof, a current controller, said lever mechanism having a part maintained in neutral or normal position relative to the current controller while the web is under proper working tension and movable therefrom in one direction or the other in response to variations in the tension of the web passing against the other portion of the lever mechanism, an electric motor operable independently of 90 the web-supply-roll shaft in circuit with the current controller and inactive or inoperative so long as the lever mechanism is in said position, but energized and rendered operative or active when the lever mechanism is actuated relatively to the current controller by a change in the tension of the web, a braking mechanism for the web-supply-roll shaft and means connecting the motor with the braking mechanism 100 operating to increase or reduce pressure on the web-supply-roll shaft in response to changes in the tension of the web.
23. The combination, in a tension regulator for printing presses and the like, of a movable member having its free end supported on the web and made sensitive and responsive to variations in the tension of said web, a current controller, a member connected to and responding in unison with 115 fluctuations of said member, the latter occupying a neutral or normal position on the current controller so long as the web is under proper working tension and movable either side of said position in response to 120
- 65 125 130

web-tension changes, means for retarding the speed of rotation of the roll from which the web is supplied, and mechanism including a normally inactive or inoperative electric motor operable independently of the web-supply-roll shaft in circuit with the current controller and made active and quickly responsive to the movement of said pivoted member in either direction from its normal or neutral position for varying the retardation caused by said means in accordance with variations in the tension of the web.

24. In a tension regulator for printing presses and the like, the combination with the web-supply-roll shaft and braking mechanism therefor, of mechanism interposed between the web and braking mechanism for automatically controlling the tension of the web, said mechanism comprising an electric motor operable independently of the web-supply-roll shaft, a pivoted lever having one end supported on the web, said lever being sensitive and responsive to variations in the tension of the web, an arm movable by the lever, a current controller over which the arm is movable in either direction from its neutral or normal position whereby the motor is energized in quick response to variations in the tension

of the web, said arm occupying the neutral or normal position on the controller and the motor being inactive or inoperative when the web is under proper working tension, and connections between the motor and the braking mechanism controlled by the former and in turn retarding the tension of the supply roll.

25. In a tension regulator for a printing press or the like, the combination of a web-roll shaft, a member movable in response to changes in the tension of the web, mechanism including an electric device for causing variations in the retardation exerted on said roll-shaft in accordance with changes in the tension of the web, and an electric controller in circuit with said electric device and actuated by said movable member to cause the operation of said mechanism in accordance with changes in the tension of the web.

In testimony whereof I hereunto set my hand in the presence of the two undersigned witnesses, this 23d day of August, 1910, at Plainfield, N. J.

IRVING A. HUNTING.
